UNITED STATES PATENT OFFICE.

HERBERT W. DREW, OF CHICAGO, ILLINOIS.

WINDOW-VENTILATOR.

1,231,340.

Specification of Letters Patent. Patented June 26, 1917.

Application filed August 30, 1912. Serial No. 717,900.

To all whom it may concern:

Be it known that I, HERBERT W. DREW, a citizen of the United States, residing at Chicago, in the county of Cook and State of Illinois, have invented certain new and useful Improvements in Window-Ventilators, of which the following is a specification.

The principal object of my invention is to provide a new and improved ventilator 10 to be used in connection with windows of dwellings or other buildings or closed vehicles. Another object of my invention is to provide a convenient window sash ventilator with means for purifying the air that 15 enters through the same. These objects and various others will be readily appreciated in connection with the accompanying description of one specific embodiment of my invention. In the drawings I have illustrated this one embodiment and I now proceed to describe the same, but it will be understood that the invention is defined in the appended claims.

Referring to the drawings—

25 Figure 1 is a vertical section showing my improved ventilator in closed position with the window also closed.

Fig. 2 shows my ventilator in use in combination with the open window.

30 Fig. 3 is a top plan view of the end members in closed relation.

Fig. 4 is an inside elevation of the same.

Fig. 5 is a top plan view of the end members in open relation.

35 Fig. 6 is an inside elevation of the same.

Fig. 7 is a perspective view of the end members spaced apart to show them more clearly; and

40 Fig. 8 is a perspective view looking across a vertical section toward the end of the device showing the ventilator members proper in readiness to be assembled with said end members.

This device is adapted to be used in combination with the ordinary window having 45 a window sill 15, the window glass 16, lower sash member 17, and side posts 18. At each side of the window an angle member 19 is fastened by screws through the holes 20 to the respective side posts 18. A similar opposed angle member 21 is pivoted to the angle 19 at 22. The links 23 pivoted at 24 connect these two angle members 19 and 21.

Hanging from the pivot 24 is a gore shaped 55 piece of sheet metal 25 that bridges across

the space between the angles 19 and 21 when they are opened apart. The tongue 26 turned in from the edge of the angle 19 limits the movement of the plate 25 and the tongue 27 turned in likewise limits the movement of the jointed links 23. A washer 28 between the angles 19 and 21 at the pivot 22 spaces them apart so as to make room between them for the links 23 and the plate 25.

The inturned flange 21' of the angle 21 has 60 holes 29 with adjacent slots to receive the heads of the screws 34 carried by the deflector.

This deflector 30 is a rectangular glass mounted in a wooden frame whose side members are 33 carrying the screws 34. Hinged to the deflector 30 at its lower edge by the hinge 32 is a woven wire screen 31 mounted in a rectangular wooden frame.

When the deflector 30 and the screen 31 75 are spaced apart in V-shape, as shown in Fig. 8, a cloth filter 35 stretches across their upper edges. The outside and inside edges of the cloth 35 are doubled, as indicated at 36, and small metal rods 37 are slipped within 80 the folds 36. Clips 38 on the upper edges of the deflector 30 and screen 31 are adapted to have the rods 37 thrust under them, thus holding the outside and inside edges of the cloth 35 to the upper edges of the screen 31 85 and the deflector 30 respectively.

At the sides of the window the cloth 35 is extended and tapered to form the flaps 41. The edges of these flaps 41 are provided with push fasteners 39, like glove fasteners, and 90 studs 40 are provided on the adjacent edges of the deflector and screen frames to receive the fasteners 39.

When the window is closed and the device 95 is not in use it may be folded up, as shown in Fig. 1. When desired to ventilate the window the window sash can be raised, as shown in Fig. 2, and the deflector 30 swung into the room, thus stretching the filter cloth 35 out, as shown in Fig. 2. When it is desired to remove the apparatus from the window the screen 31 can be swung into the room from the position shown in Fig. 2 and then both deflector 30 and screen 31 with the filter cloth 35 can be lifted out and taken aside by disengaging the screws 34 from the holes 29.

I claim:

1. In a window ventilator, a stationary member to be rigidly attached to the side 100

- post of a window casing, another member pivoted to said fixed member at their lower ends, jointed links connecting the upper ends of the fixed and movable members, and a floating filler plate attached to said jointed links at their intermediate point, said filler plate being adapted to close the space between said fixed and movable members when they are spread apart.
- 10 2. In combination with a window frame and a window sash of the type adapted to be raised and lowered in the frame, end members attached to the side posts of said frame, and a deflector and screen of equal length hinged together along their lower edges and adapted to be dropped into said end members and retained in operative position thereby.
- 15

3. In a window ventilator, two members pivoted together at their lower ends, links 20 pivoted to the upper ends of said members, said links being pivotally connected to each other at their free ends, a filler plate pivoted to said links where they are pivoted to each other and arranged to close the space between said members when they are spread apart, and a stop on one of said members to limit the range of movement of said filler plate.

In testimony whereof, I have subscribed 30
my name.

HERBERT W. DREW.
